UNITED STATES PATENT OFFICE.

WILLIAM E. STEVENS, OF NEW HAVEN, CONNECTICUT, ASSIGNOR TO SARGENT & COMPANY, OF NEW HAVEN, CONNECTICUT, A CORPORATION OF CONNECTICUT.

DESIGN FOR CASKET-TRIMMING.

42,093.

Specification for Design.

Patented Jan. 9, 1912.

Application filed September 28, 1911. Serial No. 651,868. Term of patent 14 years.

To all whom it may concern:

Be it known that I, WILLIAM E. STEVENS, of the city and county of New Haven and State of Connecticut, have invented a new, original, and ornamental Design for a Casket-Trimming, of which the following is a specification, when taken in connection with the accompanying drawings, which form a part thereof, and in which—

Figure 1 represents a side elevation of a

casket trimming embodying my new, original and ornamental design, and Fig. 2 represents an edge view of the same.

What I claim is:—

The ornamental design for a casket trimming, as shown.

WM. E. STEVENS.

Witnesses:

WILLIAM A. RICE,
EDWARD R. SARGENT.
